SwedenApplication August 16, 1943, Serial No. 498,820
In Sweden July 29, 1940

6 Claims. (Cl. 229—14)

1

The present invention relates to packages of the type including a box of cardboard or the like and a lining inserted therein.

An object of the invention is to provide a package of this type which is especially adapted for finely divided contents because it encloses the contents practically air-tightly and positively prevents even the most finely divided contents from leaking out.

Another object of the invention is to provide a package of the said type which is easy to manufacture at reasonable cost.

Still another feature of the invention is to provide a package of said type which is easy to close tightly after filling.

In the accompanying drawings:

Figs. 1-3 illustrate an embodiment of the invention, and

Figs. 4-8 illustrate another embodiment thereof;

Fig. 1 is a plan view of a blank for the package of the first embodiment;

Fig. 2 is a perspective view of one end of this package in open state;

Fig. 3 is a perspective view of said end in a partially closed state;

Fig. 4 is a plan view of the blank for a package of the second embodiment;

Fig. 5 is a perspective view of one end of this package in open state;

Fig. 6 is a perspective view of same end subsequent to the first closing stage;

Fig. 7 is a top plan view of the same end at this first closing stage;

Fig. 8 is a perspective view of the same end prior to the final closing stage.

With reference to Fig. 1, the full heavy lines represent the outline of the blank of the cardboard box whereas the dash-dot heavy lines indicate the outline of the lining. The full thin lines indicate folding indications formed in the card board blank and the dash-dot thin lines indicate borders for sticking the lining on the cardboard blank. The cardboard blank is formed with longitudinally extending folding indications 1 and transversely extending folding indications 2 dividing the cardboard blank into two side panels 3, two narrower panels 4, and two wider and two narrower end panels 5¹, 5² and 6, 6 respectively, at each end. In addition, the cardboard blank includes a pasting portion 7. Those wider end panels which are indicated by the numerals 5¹ are separated from the adjacent narrower end panels by cuts 8 so as to form separate flaps only connected with the respective wider main panels

2

3 at their base lines 2. The narrower end panels 6 are each formed with a diagonally extending folding indication 9 extending to the free corner or point as produced by the respective cut 8.

The outline 10 of the lining is substantially rectangular and projects beyond the end 5 of the cardboard blank. Opposite each of the wider end panels 5¹ of the cardboard blank adapted to form separate flaps a portion of the lining is cut away down to the top 12 of a trapezium area the bottom of which is represented by the base line 2 of the flap 5¹ and the sides of which are the two inclined lines 11. Within said trapezium area the lining should, preferably, be pasted to the flap 5¹. The lining has no cuts corresponding to the cuts 8 of the cardboard blank, there being no incisions at all made in the outline of the lining except at 13, 12 as just described.

In forming a package of the composite blank shown in Fig. 1 the blank is first folded along the lines 4 and the portion 7 is pasted to the right-hand panel 3. The result will be an open-ended tube of rectangular cross section, as shown in Fig. 2, with the lining 10 projecting beyond the edges of the end panels 5¹, 5², 6, 6. In order to manually close said tube at each open end the two narrower end panels 6 are pressed inwards by the forefingers, causing said panels to fold themselves double along the diagonal folding indications 9 and bring the wider panel 5² with them. By exerting a pressure with the thumbs on said wider end panel 5², the latter is pressed down so as to lie flat against the double folded panels 6, 6 in a plane at right angles to the surfaces 3, 4 of the box. By the folding operation described, the lining 10, which is assumed to be pasted to the separate flap 5¹ along the trapezium area bounded by the lines 2, 12 and 11, 11, is double folded against the separate flap 5¹ with the portions 14, 15 bounded by the lines 13, 13 overlapping each other, as shown in Fig. 3. The portions of the lining 10 projecting above the upper edges of the end panels 6, 6 and 5² project after the folding operation described in double-folded state between the upper, or free, edge of the end panel 5² and said overlapping portions, as shown in Fig. 3. It is seen from this figure that the mouth portion of the lining projecting beyond the upper, or free, edge of end panel 5², is tightly compressed between said free edge and the base line of the separate flap 5¹. By folding down the separate flap 5¹ it comes into contact with the end panel 5², the projecting mouth portion of the lining will be folded around the free edge of the end panel 5² and thus made quite

powder-tight, and may then be sealed in this state by pasting the separate flap 5¹ to the end panel 5².

In folding the end panels of the package above described it may happen, if the folding is carelessly made, that the mouth portion of the lining does not exactly partake in the folding of the end panels of the cardboard box but wrinkles, thereby jeopardizing the sealing effect desired. This risk may be overcome by modifying the cardboard blank so as to allow it to more positively guide the lining during the folding operation, as will hereinafter be described with reference to Figs. 4-8 of the drawings. As far as possible the same reference numerals and the same manner of illustration are used in these figures as in the Figures 1-3 already described.

Thus, in Fig. 4, the outline of the cardboard of box blank is indicated by thick full lines and the outline of the lining blank by thin dash-dot lines. The cardboard blank is provided with four parallel longitudinal folding indications 1 and two transverse folding indications 2 near either end. These folding indications divide the blank into a set of panels or fields, viz. two wider side panels 3, two narrower side panels 4, an additional side portion 7 for pasting purposes, and corresponding end panels.

The end panel corresponding to one wider side section 3 is designated by 5² and has no folding indications. The narrower end panels designated by the reference numeral 6, are provided with diagonal folding indications 9 as in the embodiment above described. The remaining end panels, belonging to the other side panel 3, are each formed with a transverse cut, indicated by the thick dotted line 16, and two longitudinal cuts 8, extending from the base lines 2 of the adjacent narrower end panels 6 to the ends of the cut 16. Thus, each of these end panels is divided into an inner separate flap 5¹ coherent with the respective side panel 3 and an outer ribbon-like portion 17 forming a sort of bridge between the adjacent end panels 6. Said ribbon like portion 17 is formed with two longitudinally extending folding indications 18 lying at a distance from the respective folding indications 1 equal to a fourth of the length of the ribbon-like portion 17. In addition, said portion 17 is formed with oblique folding indications 19 situated like "reflections" of the diagonal folding indications 9 of the adjacent end panels 6. Regard to the thickness of the cardboard or other material used for the box blank necessitates, in practice, certain corrections of the placing of the various folding indications, as illustrated in respect to the folding indications 2 in Fig. 1.

The lining 10 which projects beyond the end portions of the cardboard blank should, preferably, be pasted to the end panels 5², 6 and 17 but not to the separate flaps 5¹. A transverse pasting strip, however, may be provided on the respective side panel 3 at a small distance from the base lines of the separate flaps, as indicated at 20.

In order to form a package of the composite blank shown in Fig. 4, the blank is first folded along the indications 1 and pasted along the portion 7 so as to form an open-ended tube of rectangular cross section, as shown in Fig. 5. To close the open end shown in this figure, the tube is grasped with both hands with the separate flap facing the operator. With the forefingers the two narrow end portions 7 are pressed inwards, and at the same time the middle fingers are pressed against the "rear" end section 5². At the starting of these

manipulations it is preferred to exert a weak pressure on the ribbon-like member 17 in order to cause it to yield inwards. The end sections 6 when thus pressed inwards are folded along the diagonal indications 9 and the member 17 when yielding inwards is folded along the indications 18 and 19, as will appear from Figs. 6 and 7. After the said folding operations have been completed and the "rear" end panel 5² has been pressed down as far as possible, so that its free edge is situated right opposite the base line of the separate flap 5¹, the ribbon-like member 17 will lie doubled between said "rear" end panel 5² and the double-folded end panels 6. The lining pasted to the cardboard blank members 5², 6 and 17 has been positively caused to exactly partake in the folding movements of said members of the cardboard blank. As a result, the mouth portion of the lining projecting between the free edge of end panel 5² and the base line of the separate flap 5¹ will present a smooth and tight folding in convolutions as shown in Fig. 8. Since the ribbon-like member 17 has a height midway between its ends which is equal to half the height of the undivided end panel, the portion of the lining corresponding to this end panel will be folded around the middle of the ribbon-like member and will thus be held even, and positively prevented from bending or being torn in two. In this position the mouth portion of the lining projecting between the free edge of the end panels 5², 6 and 17, bears in its folded state against the separate flap 5¹ which remains in its original position (Fig. 8). As said flap is folded down towards the previously folded down end panel 5², it will fold said portion around the free edge of the end panel 5², thereby powder-tightly closing the lining. By pasting the folded down flap to the end panel 5² the package is sealed in closed position.

What I claim is:

1. A package for the purpose set forth, comprising a box of stiff material and an unsalted lining inserted therein, said box having side panels and, at least at one end, a set of top panels foldably connected with the respective side panels of the box for closing the package, one of said top panels being a separate closing flap, while the remaining top panels are joined with adjacent top panels at the corners of the box, two of said top panels having fold lines extending diagonally from their free top corners to their bottom corner which is connected with an adjacent top panel, the lining being longer than the box so as to project beyond the upper edges of the top panels, so that upon folding down the said coherent top panels to close the respective end of the package the projecting mouth portion of the lining extends in the folded down state of said coherent end panels up between the base of the separate flap and the upper edge of the opposite one of the coherent end panels and may be folded around said upper edge and jammed between the separate flap and said opposite end panel by folding the separate flap down against said opposite end panel and be sealed in said position by pasting, the lining being pasted to the box adjacent the base of the separate flap to retain the lining in position especially during the folding operations.

2. A package as claimed in claim 1, in which the separate flap comprises a whole end panel of the box.

3. A package as claimed in claim 1, in which

the separate flap comprises a portion only of an end panel of the box.

4. A package as claimed in claim 1, in which the separate flap comprises a whole end panel and in which the lining is attached to said flap along a substantially trapezium-shaped area, the bottom of which is represented by a folding indication between the end panel and the respective side of the box, a part of the lining in contact with said flap being cut away down to the top of said trapezium area.

5. A package for the purpose set forth, comprising a box of stiff material and an unslotted lining inserted therein, said box having side panels and, at least at one end, a set of top panels foldably connected with the respective side panels of the box for closing the package, one of said top panels being a separate closing flap, while the remaining top panels are joined with adjacent top panels at the corners of the box, two of said top panels having fold lines extending diagonally from their free top corners to their bottom corner which is connected with an adjacent top panel, one of the end panels of the box consisting at one end of an inner member forming a separate flap directly connected to the respective side of the box along a folding indication but free at its outer edges, and an outer member forming a ribbon-like bridge between the adjacent end panel so that the end panels will be together all around at their upper edges, the lining being longer than the box so as to project beyond the upper edges of the top panels, so that upon folding down the said coherent top panels to close the respective end of the package the projecting mouth portion of the lining extends in the folded down state of said coherent end panel up between the base of the separate flap and the upper edge of the opposite one of the coherent end panels and may be folded around said upper edge and jammed between the separate flap and said opposite end panel by folding the separate flap down against said opposite end panel and be sealed in said position by pasting, the lining being pasted to the box adjacent the base of the separate flap to retain the lining in position especially during the folding operations.

6. A package for the purpose set forth, comprising a box of stiff material and an unslotted

50

lining inserted therein, said box having side panels and, at least at one end, a set of top panels foldably connected with the respective side panels of the box for closing the package, one of said top panels being a separate closing flap, while the remaining top panels are joined with adjacent top panels at the corners of the box, two of said top panels having fold lines extending diagonally from their free top corners to their bottom corner which is connected with an adjacent top panel, the separate end closing flap comprising a portion only of an end panel, the remaining portion of the end panel forming a ribbon-like bridge between two adjacent end panels having diagonal folding indications, said ribbon-like portion being provided with folding indications for enabling an automatic double folding thereof when the said adjacent end panels are folded along their diagonal folding indications, the lining being longer than the box so as to project beyond the upper edges of the top panels, so that upon folding down the said coherent top panels to close the respective end of the package the projecting mouth portion of the lining extends in the folded down state of said coherent end panels up between the base of the separate flap and the upper edge of the opposite one of the coherent end panels and may be folded around said upper edge and jammed between the separate flap and said opposite end panel by folding the separate flap down against said opposite end panel and be sealed in said position by pasting, the lining being pasted to the box adjacent the base of the separate flap to retain the lining in position especially during the folding operations.
